(57) **CLAIM**

The ornamental design for electronic device holder for a wrist band, as shown and described.

DESCRIPTION

FIG. 1 is a perspective view of our new electronic device holder for a wrist band design;

FIG. 2 is a top view of our new electronic device holder for a wrist band design;

FIG. 3 is a right side view of our new electronic device holder for a wrist band design, which is the same as a left side view;

FIG. 4 is a bottom view of our new electronic device holder for a wrist band design; and,

FIG. 5 is a front end view of our new electronic device holder for a wrist band design, which is the same as a rear end view. The broken lines are for illustrative purposes only and form no part of the claimed design.

1 Claim, 5 Drawing Sheets
